CLAIM

The ornamental design of a chafing dish, as shown and described.

DESCRIPTION

The present application is related to commonly-assigned U.S. Design patent application Ser. No. 29/378,381, entitled “Chafing Frame,” U.S. Design patent application Ser. No. 29/378,383, entitled “Chafing Griddle,” U.S. Design patent application Ser. No. 29/378,385, entitled “Chafer Wok,” and U.S. Design patent application Ser. No. 29/378,387, entitled “Soup Chafer,” which are filed concurrently herewith and which are incorporated by reference herein in their entireties for all purposes.

FIG. 1 shows a perspective view of a chafing dish showing a first embodiment of our design;

FIG. 2 shows a front elevation view of the chafing dish of FIG. 1;

FIG. 3 shows a right side elevation view of the chafing dish of FIG. 1;

FIG. 4 shows a rear elevation view of the chafing dish of FIG. 1;

FIG. 5 shows a left side elevation view of the chafing dish of FIG. 1;

FIG. 6 shows a top plan view of the chafing dish of FIG. 1;

FIG. 7 shows a bottom plan view of the chafing dish of FIG. 1;

FIG. 8 shows a perspective view of a chafing dish showing a second embodiment of our design;

FIG. 9 shows a front elevation view of the chafing dish of FIG. 8;

FIG. 10 shows a right side elevation view of the chafing dish of FIG. 8;

FIG. 11 shows a rear elevation of the chafing dish of FIG. 8;

FIG. 12 shows a left side elevation view of the chafing dish of FIG. 8;

FIG. 13 shows a top plan view of the chafing dish of FIG. 8; and,

FIG. 14 shows a bottom plan view of the chafing dish of FIG. 8.

The broken lines are included for the purpose of illustrating portions of the chafing dish that form no part of the claimed design.
